UNITED STATES PATENT OFFICE.

JOHN HENRY WHITEHEAD, WILLIAM EDWARD LAYLAND, AND GEORGE GALLOWAY,
OF LEEDS, ENGLAND.

BEARINGS FOR THE DRAWING-OFF ROLLERS OF NOBLE'S COMBING-MACHINES.

1,102,834.

Specification of Letters Patent. Patented July 7, 1914.

Application filed May 5, 1913. Serial No. 765,561.

To all whom it may concern:

Be it known that we, JOHN HENRY WHITEHEAD, WILLIAM EDWARD LAYLAND, and GEORGE GALLOWAY, subjects of the King of Great Britain and Ireland, residing at Leeds, in the county of York, England, have invented certain new and useful Improvements in or Relating to Bearings for the Drawing-Off Rollers of Noble's Combing-Machines, of which the following is a specification.

Our invention refers to supports or bearings for the spindles of the drawing-off rollers of Noble's combing machines. With the usual constructions of such supports or bearings, there is a liability after a little wear and owing to the pull of the sliver and the thrust of the spring which pushes the loose roller toward the driving roller, of the shorter spindle which carries the loose roller taking a position out of line with, *i. e.* not parallel to the longer spindle, with which the driving roller is usually integral. Also the slide blocks, in which the holes forming the bearings for the short spindle are made, often tilt upward at one end under the pressure of the said springs behind them, throwing them out of true.

Now the object of this invention is to avoid these disadvantages, and also to lessen the cost and labor of making such bearings. We attain these objects by the construction illustrated by the accompanying drawings, to which reference is had in the following description.

Figure 1 is a vertical section of our improved support or bearing through the axes or both rollers. Fig. 2 is a plan view on line A A of Fig. 1. Fig. 3 is a plan view of one of the slide blocks, and Figs. 4 to 7 are cross sections on lines B B, C C, D D and E E respectively of Fig. 1.

The same reference letter is used for the same or corresponding part in all the views.

45 *a* is the driving roller and *b* are the ends of the spindle of the same, which may be formed integral with the roller as shown.

c is the loose roller and *d* is the spindle of the same.

50 According to this invention, the slide or guide *e* for the slide block *g*, carrying or forming the bearing for the spindle *d* of the loose roller, is formed as a hollow cylinder open at one end, and closed at the other end

f; and the slide block *g* is formed as a more or less solid cylinder fitting the interior of the guide *e*, which is also made cylindrical. The slide block has a hole *h*, see Fig. 3 diametrically through it near its front end, which forms the socket or bearing for the end *d* of the spindle of the loose roller. The front or open end of the hollow cylindrical guide *e* is provided with a hole *i* Fig. 2, diametrically through its sides, so as to receive the vertical bush *k* forming the bearing for the spindle *b* of the driving roller *a*.

The underside of the guide *e* for the lower end of the driving roller spindle *b* is provided with a plug and socket projection *l* Fig. 1, the socket hole of which is a continuation of said hole *i*, the turned outside of the projection *l* fitting in a socket hole formed in the bracket or support *m* carrying the gearing plate *n*. *o* is a flange, by means of which the guide *e* is bolted in position and to the bracket *m*. The portion of the hole *i* in the upper side of the guide *e* is extended rearwardly for a short distance as a slot hole *p*, for the purpose of giving passage for the said spindle to the socket or bearing hole *h* in the slide block *g*. A groove *q* is formed along one side of the slide block *g* into which the turned down end of a screw *r*, passed through the side of the cylindrical guide *e*, projects; for the purpose of preventing any partial rotation of the slide block *g* when the spindle *d* is withdrawn, so that there is no difficulty in reinserting the end of the spindle in the bearing hole *h* in the slide block. A circular recess *s* extends inward from the rear end of the slide block *g* to receive the greater part of the length of the usual spiral spring *t* for pressing the loose roller toward the driving roller. The usual screw *u* for adjusting the pressure, passes through the closed rear end of the guide *e*, and its conical inner end bears against a deep countersink formed in the head of the thrust pin *v*, the shank of the latter fitting within the rear end of the spiral spring *t*. With the omission of the projection *l* and the flange *o*, the construction of the bearing support for the upper ends of the spindles of the loose and driving rollers is an exact inverted counterpart of that just described for the lower ends of said spindles. The guide *e* for the upper ends of the spindles is car-

ried from the guide for the lower ends of the same by the usual supporting plate or bracket *w*.

It will be evident that the cylindrical construction of the slide blocks and guides very much facilitates and cheapens the construction, and provides a guiding surface all around the guide blocks; while the recessing of the guide blocks to receive the springs allows the guide blocks to be correspondingly lengthened and a longer guiding surface to be obtained, while the point of application of the spring pressure is kept well toward the front of such guiding surface; all of which contribute toward keeping the loose roller accurately parallel with the driving roller, and to lessen the wear of the working surfaces.

Having now particularly described our invention what we claim is—

In combination with a pair of drawing off rollers for a combing machine and means for driving guides at right angles to said rollers, each guide being provided with a tubular extension and a pair of opposite

openings in the side-wall thereof, pair of cylindrical bearings for the journals of the driving roller, each of said bearings being fitted into a pair of said openings, a pair of cylindrical slides movable respectively lengthwise in said guides recessed in their rear end and provided at their lower ends with bearings, for the driven roller of said pair, springs fitting into the rear recesses of the slides bearing against the latter, thrust pins bearing against the rear ends of said springs and adjusting screws working through the rear ends of said guides and bearing against said thrust pins, substantially as and for the purpose set forth.

In testimony whereof we have signed our names to this specification in the presence of two subscribing witnesses.

JOHN HENRY WHITEHEAD,
WILLIAM EDWARD LAYLAND,
GEORGE GALLOWAY.
